(57) **CLAIM**

The ornamental design for an insert for food bowl, as shown and described.

DESCRIPTION

FIG. 1 is a top perspective view of an insert for food bowl showing my new design.

FIG. 2 is a bottom perspective view of the insert for food bowl shown in FIG. 1.

FIG. 3 is a front view of the insert for food bowl shown in FIG. 1.

FIG. 4 is a back view of the insert for food bowl shown in FIG. 1.

FIG. 5 is a right side view of the insert for food bowl shown in FIG. 1.

FIG. 6 is a left side view of the insert for food bowl shown in FIG. 1.

FIG. 7 is a top view of the insert for food bowl shown in FIG. 1.

FIG. 8 is a bottom view of the insert for food bowl shown in FIG. 1.

FIG. 9 is a cross-sectional view of the insert for food bowl taken along line 9-9 shown in FIG. 7.

FIG. 10 is a perspective view of the insert for food bowl shown in an environment of use; and,

FIG. 11 is a perspective view of the insert for food bowl shown in an alternate environment of use.

The broken lines illustrating additional inserts and a bowl in FIGS. 10 and 11 show environment and form no part of the claimed design.

1 Claim, 9 Drawing Sheets
